(57) **CLAIM**

We claim the ornamental design for a knock box, as shown and described.

DESCRIPTION

FIG. 1 is a front view of the knock box;

FIG. 2 is a back view of the knock box;

FIG. 3 is a left side view of the knock box; the right side view

is a mirror image of the left side view;

FIG. 4 is a top view of the knock box;

FIG. 5 is a bottom view of the knock box; and,

FIG. 6 is a perspective view of the knock box.

The broken lines indicate the bounds of the claimed design and form no part of the claimed design.
